UNITED STATES PATENT OFFICE.

CHARLES D. MOSHER, OF NEW YORK, N. Y., ASSIGNOR, BY MESNE ASSIGNMENTS, TO THE BABCOCK & WILCOX COMPANY, OF BAYONNE, NEW JERSEY, A CORPORATION OF NEW JERSEY.

STEAM-BOILER.

1,192,928.

Specification of Letters Patent. Patented Aug. 1, 1916.

Application filed January 31, 1912. Serial No. 674,627.

To all whom it may concern:

Be it known that I, CHARLES D. MOSHER, a citizen of the United States, residing in the borough of Manhattan of the city of New York, in the State of New York, have invented certain new and useful Improvements in Steam-Boilers, of which the following is a specification, reference being had to the accompanying drawings, which

10 form a part hereof.

The object of this invention is to promote the combustion of fuel in the furnaces of steam boilers, and particularly of boilers of water tube type.

15 It is well known that in order to obtain the most perfect combustion the gases should be burned in a chamber completely surrounded by fire brick or other refractory material, and further should be thoroughly

20 mixed with the necessary air, while the furnace should be so arranged that if there is any excess of air or gas locally distributed in any part it will be mixed with the bulk of gas and so averaged and burned before

25 entering among the tubes. Experience has proved that the gases, when brought in contact with the tube surface of a boiler, are cooled down below the temperature of combustion and are extinguished and that in order

30 that complete and smokeless combustion may take place the fuel gases should be burned in a brick chamber before they enter among the tubes. To insure these necessary conditions in boilers of the type referred to, 35 and thereby attain the purpose of the invention there is arranged above the main zone of combustion, whether of solid, liquid or gaseous fuel, a perforated screen of refractory material which becomes incandescent

40 and thereafter, by maintaining a zone of intense heat at some distance above the fire, promotes the complete combustion of gases which, though released by the fire, pass off in a state of incomplete combustion. The

45 intense heat of the screen causes the screen to act as an igniter for the unburned gases which pass through its perforations and the screen also forms, in effect, a secondary combustion chamber above the primary or

50 main combustion chamber. It acts also as a mixer of the gases which pass off from the fire and in this way promotes combustion. In addition to the air which is admitted through the primary combustion chamber

55 and is sufficient to support combustion there-

in, it is generally desirable to admit additional air in proximity to the screen to support combustion of the gases which takes place above the screen, the incoming air currents also acting as stirrers to promote further the mixture of the gases. It is practically impossible to make a perforated arch of the usual construction stand in such a location and therefore, in accordance with the present invention, it is supported by generating tubes of the boiler itself, since such tubes, being filled with water and forming part of the circulatory system of the boiler, are thereby prevented from being burned out by the intense heat in the combustion chamber. It is preferable, moreover, to have such tubes protected from the impingement of burning gases by the refractory material of which the screen is formed.

The invention is capable of application to 75 boilers of different types and is illustrated in the accompanying drawings as embodied in boilers of different types.

In such drawings—Figure 1 is a view in vertical transverse section of a portion of a 80 water tube boiler adapted for oil fuel and to which the invention is applied. Fig. 2 is a view of the same in longitudinal, vertical section. Fig. 3 is a view similar to Fig. 1 but showing a boiler adapted for solid fuel. Fig. 4 is a view in longitudinal, vertical section of the boiler illustrated in Fig. 3. Fig. 5 is a detail view of the perforated screen, showing its construction. Fig. 6 is a view in perspective showing two of the 90 blocks or elements of the screen shown in Fig. 5, and Fig. 7 is a sectional view showing the invention applied to another type of boiler.

The boiler shown in Figs. 1 and 2 comprises a casing *a*, a steam drum or header *b*, two water drums or headers, one of which is shown at *c* while the other is similarly placed at the opposite side of the longitudinal axis of the boiler, water tubes *d* which connect the steam drum or header with the water drum or header on the same side, and a single series or row of water tubes *e* which also connect the water drum or header and the steam drum or header and serve as a support for the reverberatory arch or screen of refractory material, there being a similar series of tubes *e'* to support a similar screen at the opposite side of the boiler. In the form of boiler indicated the screen is slightly

inclined and the tubes *e* are therefore extended inward from the water drum *c* in an upwardly inclined direction toward the axis of the boiler and are then bent upward toward the steam drum *b*. Upon the inclined portions of the tubes *e* is supported the perforated refractory arch or screen *f* of refractory material. Such arch or screen may be constructed in any convenient manner. As illustrated in Figs. 5 and 6 it is composed of complementary blocks *f*¹ and *f*² which are recessed as at *f*³ to receive the tubes *e* and are formed in adjacent sides with recesses *f*⁴ and *f*⁵ to form, when the blocks are assembled, as shown in Fig. 5, the perforations *f*⁶, and are also formed with overlapping edges as at *f*⁷ so as to break the joints between adjacent blocks. No burner nozzles for either fuel oil or fuel gas are shown in Figs. 1 and 2, but it is presumed that this boiler is adapted for the burning of either fuel oil or fuel gas, there being no grate bars shown. The fire-brick walls *g* are shown as provided with openings *g*¹ for the admission of additional air in proximity to the screen *f* to mix thoroughly the gases which pass off from the primary combustion chamber and to support the combustion of such gases when they are ignited by the incandescent screen, which ignites the gases and promotes the mixture thereof as well.

The boiler shown in Figs. 3 and 4 is generally similar to that shown in Figs. 1 and 2, comprising a casing *a*, a steam drum *b*, water drum *c*, water tubes *d*, and additional series of water tubes *e* and *e*' which support the perforated screen *f*. It is assumed that this boiler, however, is adapted for the burning of solid fuel, a grate being shown at *h*. The fire-brick walls are also shown as provided with openings *g*¹ for the admission of air in proximity to the screen.

The boiler shown in Fig. 7 is of a different form from that shown in Figs. 1 and 3, comprising a casing *a*', a steam drum *b*' and a single water drum *c*' connected by water tubes *d* with the steam drum. In this boiler there is also shown a single series or row

of water tubes *e*' which are extended in an upwardly inclined direction from the water drum *c*' and are then bent upward toward the steam drum *b*', the inclined portions of these tubes supporting the perforated reverberatory arch or screen *f* as before. This boiler is shown as provided with grates *h*' for the burning of solid fuel and the fire-brick walls *g* are shown as having openings *g*' for the admission of air in proximity to the screen.

In the forms of boilers shown in Figs. 1, 3 and 7 the perforated reverberatory arch or screen is shown as slightly inclined, forming a secondary combustion chamber between the screen and the water tubes.

Various other applications and embodiments of the invention will readily suggest themselves and it will be understood that the invention is not restricted to the particular arrangements nor to the particular details of construction of the perforated screen shown and described herein and may be applied to boilers of various types.

I claim as my invention:—

In a water tube boiler of the inclined bank type, a combustion chamber having refractory side walls and provided with a perforated refractory screen arranged below and at an angle to the bank of tubes and through which the gases rise before reaching the tubes, said screen forming a secondary combustion chamber of general triangular form between it and the bank of tubes, and water tubes supporting said refractory screen and connected at their ends to upper and lower water spaces of the boiler, the refractory side walls of the setting having air inlet openings in proximity to the refractory screen to aid the secondary combustion; substantially as described.

This specification signed and witnessed this 30th day of January A. D., 1912.

CHARLES D. MOSHER.

Signed in the presence of—

D. DAMES,
WORTHINGTON CAMPBELL.

Copies of this patent may be obtained for five cents each, by addressing the "Commissioner of Patents, Washington, D. C."

It is hereby certified that in Letters Patent No. 1,192,928, granted August 1, 1916, upon the application of Charles D. Mosher, of New York, N. Y., for an improvement in "Steam-Boilers," an error appears in the printed specification requiring correction as follows: Page 1, line 32, after the word "brick" insert the word *lined*; and that the said Letters Patent should be read with this correction therein that the same may conform to the record of the case in the Patent Office.

Signed and sealed this 22d day of August, A. D., 1916.
